LOCKING SWITCH

Ernest H. Jacobs, River Forest, Ill., assignor to
 Electrical Engineers Equipment Co., Melrose
 Park, Ill., a corporation of Illinois

Application June 19, 1930, Serial No. 462,212

12 Claims. (Cl. 200—169)

This invention relates, generally speaking, to switches for use in connection with electrical equipment and is concerned with an improved locking switch and more particularly with a manually operated switch employed in connection with electrical equipment operating on high amperages, and having means for locking the switch in closed position.

A switch of this type, in the simplest embodiment, comprises stationary contact members, so called contact clips or jaws, and movable contact blades for engaging the contact clips to close or to open an electrical circuit.

It is desirable that such a disconnecting switch should be installed in a place which is not readily accessible to the attendants without using special tools for reaching the switch when its operation is desired. This precaution is necessary for protecting the attendants as well as the equipment, and will be understood when considering that such a switch may be employed in connection with circuits carrying high capacities of current, in certain cases exceeding several thousand amperes. The switch is therefore devoid of operating handles and the like, but is provided with eyelets of various forms, or with suitable latches adapted to be engaged by a so called hook stick or hook pole for moving the connecting blades of the switch in and out of contact with the stationary clip.

There is also a locking mechanism provided for definitely locking the switch in closed position. The use of a hook pole for operating the switch actuates the locking mechanism to release the blades preparatory to dislodging the same from contact with the clip. This involves a deliberate premeditated act on the part of the attendant to the end of safeguarding the electrical equipment which might be damaged by accidental opening of the switch, and also to protect the linemen and attendants at work.

It is the purpose of the instant invention to produce a novel locking mechanism for a switch of the type explained, and to provide a simple and efficient means for spreading the blades prior to releasing the locking mechanism and before exerting a pull to move the blades out of contact with the stationary clip. The invention is characterized by several novel structural and functional features, which are provided to take care of a number of requirements as briefly indicated below.

It is desirable that the mechanism for locking the switch should be disposed outside of the main path of current so that preferably no current

flows through the locking mechanism itself. This is to protect the locking mechanism against the detrimental effects of heating and arcing and also against the magnetic effects of the current passing through the switch.

Another requirement resides in the desirability of providing means for breaking the corrosive seal which might obtain between the blades and the contact clip prior to opening the switch, and preferably combining the actuation of these means with the actuation of the locking mechanism.

According to a further requirement, it seems desirable that the locking mechanism and the means for spreading the blades, should be protected.

The switch of my invention, which I will later on describe in detail, comprises two stationary contact clips mounted on a suitable base. Two cooperating companion contact blades are rotatably attached to one of the stationary clips. The other clip is provided with a recess for receiving a locking lever. This lever is angular and mounted rotatably between the blades, outside of the main path of current flow when the switch is in closed position, and is movable with the blades. A spring is provided which tends to move the angular locking lever in a direction to engage the recess on the stationary clip and to thereby lock the blades in engagement with the clip. An eyelet is rotatably mounted between the blades, movable therewith, and adapted, when operated by a hook pole, to move the angular lever to unlock from the stationary clip, thereby releasing the blades. During this operation, the arm of the eyelet acting upon the locking lever also spreads the blades slightly apart to break the corrosive seal. The eyelet is further provided with a cam for engagement with the face of the stationary clip, and this cammed portion of the eyelet provides for leverage to accomplish the opening operation in a simple and very efficient manner. Pairs of stop members are provided on the eyelet and adapted to cooperate with the blades to limit the movement of the eyelet relative to the blades and to transmit the force, applied to the eyelet by the hook pole for closing or for opening the switch, efficiently to the blades for moving the same in and out of contact with the clip.

It will be seen that in this arrangement, the requirements set forth previously are fully met. The locking mechanism and the means for spreading the blades are disposed between the blades and protected thereby. All these parts

are outside of the path of the main current. The structure is simple, durable, and efficient. A minimum number of parts are provided which cooperate in a positive, reliable and safe manner 5 under any reasonable operating conditions. The structural strength of the arrangement is amply adequate to meet the service.

Some of the principal objects and features which are accomplished by my invention are 10 enumerated separately in the following brief statements of objects.

One object of the invention is concerned with a disconnecting switch of the floating blade type, having a locking mechanism disposed within the 15 blades, movable therewith, and disposed outside of the main path of current flow, and a movable eyelet provided on the blades and movable therewith and having a lever to cooperate with said locking mechanism at all times regardless of the 20 position of the eyelet during the closing or opening operation.

Another object relates to the provision of a locking mechanism comprising a movable angular spring controlled lever disposed within the 25 blades of the switch and movable therewith, and adapted to cooperate with a recess or notch in the stationary contact clip to lock the blades on said clip in operating position.

Still another object is concerned with the provision of angular projections arranged on the inside of the blades, whereby the lever arm, provided on the eyelet for actuating the locking mechanism, can spread the blades apart to break the corrosive seal prior to dislodging the blades 30 from the contact clip. Therefore, the unlocking operation also breaks the corrosive seal.

A further object relates to a cam provision combined with the eyelet for engaging the face of the contact clip during the dislodging operation, whereby a leverage is obtained which accomplishes the opening of the switch in a simpler and more efficient manner than was heretofore possible.

Another object relates to stop provisions on the eyelet for limiting its movement relative to the blades in the switch opening as well as in the switch closing direction and for directly and efficiently transmitting to the blades force applied for closing or for opening the switch.

Other objects not specifically noted above will appear as the description progresses.

The invention is illustrated in the accompanying two sheets of drawings in which:

Figure 1 shows a side view of the switch with the locking mechanism indicated in dotted lines;

Figure 2 is a partial cross section taken on line 2-2 of Figure 1 with certain parts omitted to show the essential parts represented in this figure, i. e., the provision for breaking the corrosive seal of the blades;

Figure 3 represents a top view of an operating assembly of two such switches mounted on a suitable support;

Figure 4 illustrates a side view of the locking mechanism proper and of the means for spreading the blades, with one of the blades removed to show the arrangement more clearly; and

Figure 5 is an enlarged end view of the locking mechanism and of the spreading provisions looking toward the left into the switch as shown in Figure 4, with several parts omitted for the sake of clarity.

Like reference numerals in all drawings refer to corresponding parts.

Referring now particularly to Figures 1 and 3,

there is shown a support 1 suitably mounted on brackets such as 37 by means of bolts such as 38 and 38' and nuts 39. Mounting plates such as 2 and 3 are secured to the support 1 by means of bolts 4, 5, 55, 56 and bolts 6, 7, 57, 58, respectively, and nuts 8, 9, 10 and 11. Attached to these mounting plates are contact members, such as 12 and 13. These stationary contact members are usually referred to as contact clips, and this term as used previously and hereinafter is understood to designate these contact members 12 and 13.

It may be mentioned at this point that the contact clips may be suitably connected with current conductors, such as bus bars, or, in case of an indoor installation, the bus bars may be directly utilized as terminals and united with these clips as shown for example in my Patent No. 1,515,116 of November 11, 1924.

It will be observed that Figure 3 shows a twin construction, that is, to say, two disconnecting switches mounted on the support. These two switches are alike and may either operate in common or individually. For purposes of description, it will be sufficient to describe the structure of one of these switches in detail and I have therefore applied reference numerals only to the various parts of one switch shown in Figure 3 in order to avoid encumbering the drawings. The side view of this switch, it will be remembered, is shown in Figure 1.

Continuing now the description of the structure, with reference to Figures 1 and 3, the switch comprises two suitable blades such as 14 and 40. These blades are floating with respect to the locking mechanism which I shall describe presently, the contacting areas being the only portions where the blades are clamped or bound together. The blades are rotatably mounted on the clip 12 by means of a suitable bolt and nut 15 and 47, respectively. Inserted between the nut and the bolt head, respectively, and the surface of the blades, are spring washers 16 and 48 of well known construction. Approximately in the middle of the blades are provided bolts as well as 120 spring washers and nuts for laterally securing the blades at this point. The spring washers on one side of the blades are designated by numerals 18 and 19 and the corresponding nuts are marked by numerals 17 and 20. Spring washer 46 and bolt 125 45 are shown on the other side opposite the washer 18 and nut 17. The companion washer and bolt on the other side of the washer 19 and bolt 20 are not visible in Figure 3. A similar arrangement of bolts, nuts, and spring washers for holding the upper portion of the blades are indicated in Figure 1 by reference numerals 21-24 and in Figure 3 by reference numerals 21-22 and 43-44.

A lever, which has been referred to as eyelet, is shown at 25, mounted pivotally between the 125 blades at point 25'. This eyelet is best described with reference to Figures 4 and 3. It is provided with an arm 28 for actuating the locking mechanism, and with two pairs of stops 26-42 and 27-41 for limiting and for confining its motion 140 on the blades, and for efficiently applying and for distributing the force applied to the eyelet and effective to the blades in the closing and also in the opening operation. The stops project laterally from the eyelet in pairs, as marked in 145 Figure 3 by numerals 27-41 and 26-42, respectively. During the respective movement of the eyelet, a corresponding pair of these stops will engage the blades and stop further movement of the eyelet on the blades. Force applied to the 150

eyelet after a pair of these stops has engaged the blades, will be transmitted directly to the blades for moving the same on the clips 12 either into engagement or out of engagement with the clip 13. In Figure 4, which shows the position of the eyelet in the closed position of the switch, with the locking mechanism engaging the clip 13 to prevent opening of the switch, the stop 41, lying opposite the stop 27 will be in engagement with blade 40, blade 14 being removed from the assembly in Figure 4. With the blade 14 attached, it will be apparent that stop 27 will engage this blade similar to stop 41 engaging blade 40.

The locking mechanism will be explained next with reference to Figure 4.

It will be seen that the stationary contact clip 13 is recessed at 32 to provide a locking projection 60. An angular lever having arms 31 and 33 is pivotally mounted on the shaft of bolt 23. A spring 34 is wound around this shaft, one end being attached to the pin 35 disposed between the blades, and the other end engaging the arm 33 of the locking lever, tending to move the arm 31 into engagement with the recessed portion on the clip, and to lock the arm 31 behind the projection 60.

As shown particularly in Figure 5, the locking member comprising the arms 31 and 33 is recessed to receive the spring 34, its sides 54 and 55 being pivotally mounted on the shaft 23. Now, with the switch closed as shown in Figures 1 and 4, the locking arm 31 engages the recessed portion 32 of the clip, locking behind the projection 60. Since the locking arm 31 is mounted within the blades and on the shaft 23 connecting these blades laterally, it is apparent that in effect the blades are locked to the clip and prevented from disengaging the clip until the locking arm 31 is released.

When opening of the switch is desired, the hook pole will be used and inserted into the opening 30 in the eyelet. A pull exerted on the hook pole will rotate the eyelet in the direction of the arrow shown in Figures 1 and 4, and, accordingly, the arm 28 on the eyelet will move in contrary direction and act upon the arm 33 of the angular locking lever, rotating the same until the arm 31 leaves the recess 32 and releases the blades.

Further movement of the eyelet will bring the cam 29, provided thereon, into engagement with the face of the clip 13. This cam 29 is so proportioned as to provide a gradually decreasing leverage for the opening operation. In the beginning of the opening operation, the leverage will be relatively great as may be readily seen by comparing the relative distances from the opening 30 to the point of rotation 25' and from there to the rear portion of the cam 29 which will engage the face of the clip 13 first. As the opening operation progresses, the eyelet being pulled further down in the direction of the arrows in Figures 1 and 4, the distance between the point of rotation 25' and that point of the cam which engages the face of the clip at any moment during the operation, will increase, and the leverage will, therefore, correspondingly decrease. This means in effect that a certain pull on the eyelet will exert a relatively great force in the beginning of the opening operation and that this force will gradually decrease as this operation progresses.

When considering the structure, it will be seen that this cam provision on the eyelet furnishes a very good and very efficient medium for applying the correct amount of force when needed. Rel-

atively great power is necessary upon initiating the opening operation, and as the blades leave the clip, less power is needed gradually for withdrawing the blades from the clip. The provision of the cam represents, therefore, a simple means for accurately distributing and applying the force required at any given moment during the initial opening operation of the switch.

The stops 26 and 42 will engage the blades when the opening operation has progressed to a point when the blades are almost completely withdrawn from clip 13 and ready to leave this clip. The motion of the eyelet relative to the blades will, therefore, stop. Further pull on the eyelet will now be transmitted directly to the blades by means of the stops, and will be effective to move the blades in the opening direction and out of contact with clip 13. The arm 33 of the locking mechanism and the arm 28 of the eyelet are so proportioned as to prevent the arm 28 from slipping from the arm 33 and locking behind the same. In the extreme position of the eyelet, with the blades withdrawn from the clip 13, the arm 28 of the eyelet will be in engagement with arm 33 of the locking lever, holding this lever against the force of the spring 34. In the extreme position as shown in the drawings, with the blades engaging clip 13, the arm 28 of the eyelet will be positioned relative to the locking lever approximately as shown in Figures 1 and 4. It will be seen, therefore, that the arm 28 of the eyelet remains in operating engagement with the locking lever in any position during the opening operation of the switch, and, since the closing operation takes place in reversed order, this operating engagement will also be maintained during the closing operation.

It will be seen from the above that the switch opening operation, as far as explained, includes three distinct stages. First, the locking mechanism is released. Then the cam 29 cooperates with the face of the clip to effect partial dislodging of the blades, and, finally when the blades are withdrawn sufficiently from the contact clip, further pull on the eyelet will effect the completion of the opening operation.

The mechanism for spreading the blades apart prior to moving them out of contact with the clip will be explained next.

A projection 50 and 51, respectively, is provided on each blade, as particularly shown in Figure 2. These projections are permanently attached to the blades or may be integral with the blades. The blades may be forged, but it will be preferable to punch these projections into the blades as shown in the drawings, or to attach the projections by means of welding. The projections may slope slightly toward the interior and the edges may be rounded or beveled as indicated at 61 and 62. The purpose of these projections is to spread the blades in order to break the corrosive seal prior to applying the pull which withdraws the blades from contact with the stationary clip. This spreading operation is accomplished by the arm 28 of the eyelet which also actuates the locking mechanism. Arm 28 wedges between the projections and thereby exerts a lateral force on the blades which spreads the same apart and cracks any corrosive deposits which might have accumulated. The blades are thus positively pried loose from the clip and at the same time unlocked, and the opening operation can now continue as already explained.

For closing the switch, it is merely necessary to operate the eyelet in reversed direction. The

events will take place in substantially reversed order. First the stops 27 and 41 will engage the blades. When the eyelet is pushed further to close the switch, the blades will follow the direction of the applied force due to the stops on the eyelet engaging the blades. The locking lever is ready to engage the recessed clip and, upon completion of the closing motion of the blades, it will again engage the recess 32 on the clip 13. 10 The blades and the eyelet are then in the position as shown in the drawings.

It will be seen that the locking switch as described above and as shown in the drawings, presents numerous advantageous features over 15 prior constructions. There are only very few moving parts disposed protected to the outside and out of the main path of current flow. There is utmost economy of operation due to the fact that the same parts which cooperate to unlock 20 the switch, also serve to spread the blades apart. The operation of the locking mechanism is positive and reliable and under operative control of the eyelet during any moment of its opening or closing operation. The cam on the eyelet, cooperating with the face of the clip secures positive 25 dislodging of the blades in a simple manner, and the stop members on the eyelet, cooperating with the blades insure definite application of force at the proper places during the opening or closing 30 of the switch. The arrangement as described represents an advance in the art chiefly by the novel combination of improved cooperating elements designed to simplify production and, at the same time, to render a product which is safe 35 and reliable in operation.

I have shown my invention in the particular embodiment above described. It will be understood, however, that I do not want to limit myself to this exact construction, as I may employ equivalents thereof known to the art at the time 40 of the filing of this application without departing from the spirit and from the scope of the appended claims.

What I claim as my invention is:

1. An electric switch having a stationary clip 45 and blades movably mounted thereon, a stationary companion clip, a projection on said companion clip, a spring controlled lever disposed movably between said blades for engaging said projection to lock said blades on said companion clip, an operating lever movably mounted between said blades for actuating said spring controlled lever to unlock said blades, and a cam provided on said operating lever for engaging 50 said companion clip to dislodge said blades from contact with said companion clip.

2. An electric switching device having a stationary contact clip and movable blades for engaging said clip, an angular lever disposed between and interiorly of said blades and movable therewith for locking said blades on said clip, an operating lever movably mounted between said blades and movable therewith, and means on said lever for actuating said angular lever to release 55 said blades from said clip and for spreading said blades apart prior to opening said switch.

3. An electric switch having a contact clip and movable blades for engaging said clip, locking means disposed between and interiorly of said 60 blades and movable therewith for locking said blades on said clip, means for spreading said blades, operating means movably mounted between said blades and movable therewith, a single means on said operating means for actuating 65 said locking means to release said blades from

said clip and to actuate said spreading means to spread the blades laterally for breaking the corrosive seal prior to moving said blades out of contact with said clip, and cam means on said operating means for engaging said clip to move said 80 blades from said clip.

4. An electric switch having a contact clip and movable blades for engaging said clip, locking means disposed between and interiorly of said blades and movable therewith for locking said blades on said clip, means for spreading said blades, operating means movably mounted between said blades and movable therewith, a single means on said operating means for actuating said locking means to release said blades from said clip and for actuating said spreading means to spread the blades laterally for breaking the corrosive seal prior to moving said blades out of contact with said clip, cam means on said operating means 90 cooperating with said clip for partially disengaging said blades from said clip, and means on said operating means cooperating with said blades for limiting the movement of said operating means relative to said blades and for completely disengaging said blades from said clip.

5. The combination with switch blades, a pair of contact clips, and a movable operating member mounted on the blades, of a locking mechanism mounted on and disposed between said blades outside of the main path of current flow 105 and protected by said blades, means on said operating member for releasing said locking mechanism, and cam means on said member for disengaging said blades from one of said contact 110 clips.

6. The combination with switch blades, a pair of contact clips and a movable operating member, of a locking mechanism for locking said blades on one of said clips, said locking mechanism being mounted on and disposed between said blades 115 outside of the main path of current flow and protected by said blades, pin means extending through the blades and the mechanism and supporting the mechanism, means on said operating member for releasing said locking mechanism, 120 cam means on said member cooperating with said clip for applying gradually decreasing force to disengage said blades from said clip, and means on said operating member cooperating with said blades for limiting the movement of said 125 member relative to said blades.

7. The combination with switch blades, a pair of contact clips and a movable operating member, of a mechanism for locking the switch blades in engagement with one of said clips, means for 130 spreading the blades, said spreading means and said mechanism being disposed entirely between said blades outside of the path of current flow and concealed by said blades, means on said operating member for actuating said locking means 135 to release said blades from said clip and for actuating said spreading means to spread said blades prior to removing said blades from contact with said clip, and cam means on said operating member cooperating with said clip for thereafter 140 applying gradually decreasing force to disengage said blades from said clip.

8. The combination with switch blades, a pair of contact clips and a movable operating member, of a mechanism for locking the switch blades 145 in engagement with one of said clips, means for spreading the blades, said spreading means and said mechanism being disposed entirely between said blades outside of the path of current flow and laterally protected by said blades, said oper- 150

- ating member including a single lever for actuating said locking means and said spreading means to unlock said blades from said clip and to break the corrosive seal prior to moving said blades out 5 of contact with said clip, cam means on said operating member cooperating with said clip for applying gradually decreasing force to move said blades partially from said clip, and means on said operating member cooperating with said blades 10 for limiting the movement of said member relative to the blades and for moving said blades completely from said clip to open said switch. 9. The combination with a pair of movable switch blades for engagement with a contact clip 15 and an operating member mounted movably between said blades and movable therewith for effecting the engagement and disengagement of said blades, of a locking mechanism for said blades mounted on and disposed between said 20 blades out of the main path of current flow and protected thereby and movable therewith, means on said operating member for actuating said mechanism, cam means on said member for partially effecting the disengagement of said blades 25 from said clip, and means on said member for limiting the movement thereof relative to said blades and for completely effecting the disengagement of said blades. 10. A switch including a contact and a switch 30 blade movable into and out of embracing engagement with the contact, spring means urging the blade in firm engagement with the contact, and means carried by the blade for spreading the blade from the contact against the action of the spring means upon the initiation of the switch opening operation. 11. A switch including a pair of cooperating contact making members movable into and out of embracing relation to one another, means movable with one of said members and effective upon its initial movement to spread said members and to thereafter exert a camming action to move said members apart. 12. A switch including a pair of spaced floating blades having a limited relative movement and adapted to engage a contact, a pivot pin extending through the blades and substantially outside of the region of current flow, a V-shaped latch pivoted on said pin and including a locking arm and a releasing arm, said latch lying substantially entirely between said blades, means biasing the latch about its pivot to its locking position, a second pivot pin extending through said blades and spaced from the first pin, and means for prying the blades from a contact, said last means including a pivoted switch pry-lease and operating lever carried by said second pin and having also means for engaging the releasing arm of the latch and moving the latch about its pivot to its releasing position. 100
